UNITED STATES PATENT OFFICE.

WILLIAM RAYMOND DUNCAN, OF CHICAGO, ILLINOIS, ASSIGNOR TO WILLIAM H. WADE, OF CHICAGO, ILLINOIS.

DEVICE FOR MARKING PHONOGRAPH RECORDS.

Application filed March 4, 1922. Serial No. 540,980.

To all whom it may concern:

Be it known that I, WILLIAM RAYMOND DUNCAN, a citizen of the United States, and a resident of Chicago, Cook County, Illinois, 5 have invented a certain new and useful Improvement in Devices for Marking Phonograph Records, of which the following is a specification.

This invention contemplates certain improvements on the marking device disclosed in the application of William H. Wade No. 481,763, filed July 1, 1921, and contemplates the provision of stationary means for supporting the phonograph record during the 15 marking thereof, having stationary means for engaging the edges around the center hole of the record, and for supporting and guiding the means for printing or making the impression on the record, as will herein- 20 after more fully appear.

It is also an object to provide certain details and features of construction tending to increase the general efficiency and desirability of a marking device of this particular 25 character.

To this and other useful ends the invention consists in matters hereinafter set forth and claimed and shown in the accompanying drawings in which:—

30 Figure 1 is a plan of a marking device embodying the principles of the invention, showing the phonograph disc record in position for the marking operation thereon.

Figure 2 is a vertical section on line 2—2 35 in Figure 1.

Figure 3 is a fragmentary view of a portion of the record, showing the center portion thereof after the marking device has performed the desired printing or marking 40 operation thereon.

As thus illustrated, the invention comprises a suitable base 1 at the center of which is a post or upright member 2 for engaging the center hole 3 of the record 4, which latter 45 has a smooth surface 5, as usual, between the center hole and the grooves of the record. Cloth or felt or other material 6 is preferably applied to the top of the base 1 to provide a flat and yielding support for the under side of the record during the operation 50 of printing or marking thereon. The marking means, as shown, include a disc-like body 7 provided with an upstanding handle 8, the lower portion of which latter is bored vertically to provide a guide 9 to receive the cen-

ter post 2 previously mentioned. The handle contains a coil spring 10 which bears against the movable abutment 11, the latter resting against a shoulder 12 formed inside of the handle, at the upper end of the bore 9, and a plug 13 is inserted in the upper end of the cavity occupied by the spring. Thus the spring is retained in the handle and is compressed by the upward movement of the abutment 11, when the latter engages the top 60 of the post 2, and when the handle is pressed downward to move the printing means 14 (the printing means may be a rubber stamp or die of any suitable character) into engagement with the upper surface of the 70 phonograph record, thereby to print an advertisement thereon, as shown in Figure 3 of the drawings. When the handle is released, the spring 10 will expand and raise the printing means a distance above the disc 75 record, the normal position being substantially as shown in Figure 2 of the drawings. An arrow 15 or other suitable means is provided on top of the disc 7 to enable the user to turn or rotate the handle and disc 7 until 80 the printing means are in proper position for the impression on the record.

The method of using the device is as follows: The handle 8 and the disc 7 are lifted upward and disengaged from the post 85 2, and the record 4 is then placed in position as shown, by inserting the post 2 upwardly through the hole 3 in the center of the disc record. After the disc 7 and the record 4 are relatively adjusted, by rotation 90 of the handle until the arrow 15 points in the desired direction, the handle is then pressed downward and the printing means 14 are thus brought into engagement with the smooth upper surface of the phonograph 95 record, it being understood that ink or other suitable substance is carried by the printing means to produce the desired result. To apply the ink or other substance the handle 8 can be pulled upwardly and the bottom of 100 the disc 7 can be pressed against an ink pad in the manner of an ordinary rubber stamp. The printing means are then returned to the post 2, after the phonograph record is in position, and the device is then in condition 105 for operation. Thus the means for properly positioning the phonograph record are stationary and form a stationary guide for the movable printing or marking means. It will be seen that the impression 110

made by the marking means is in the smooth space between the usual label on the record and the area covered by the grooves. In other words, a round label is usually applied at the center of the record, around the center hole, but a smooth space is left between the outer edges of this label and the said area of the grooves of the record, and the printing or marking is preferably done on this smooth exposed surface of the record, although it may be placed elsewhere without departing from the scope and spirit of the invention.

What I claim as my invention is—

15 1. In means for marking a phonograph disc record having record grooves and a smooth area, marking means disposed in position to operate upon the smooth area, means to engage the edges of the disc to position said marking means and prevent marking on said grooves, and means for operating said marking means, characterized by this, to-wit: That said means for engaging the edges of the disc are formed by 20 a stationary post serving as a guide for the movement of said marking means.

2. A structure as specified in claim 1, comprising a base to which the lower end of said post is rigidly connected, forming a 30 support for the disc when the latter is centered thereon by said post.

3. A structure as specified in claim 1, comprising a spring for yieldingly supporting the said marking means on the upper end of said post, said marking means being adapted to be removed from said post to permit the latter to enter the center hole of the disc record.

4. A structure as specified in claim 1, 40 said marking means comprising a body with

a central handle having a bore to receive said post therein, so that said marking means are rotatable on said post by turning said handle.

5. Means for marking a phonograph record, comprising marking means disposed in position to mark the record in the annular space ordinarily provided between the central label and the grooves of a disc record, and means for engaging the disc to position the latter and said marking means relatively to each other, thereby to ensure accurate placement of the marking in said annular space, characterized by this, to-wit: That said means for engaging the disc include a stationary post adapted to pass through the center hole of the disc, and forming a guide for the movement of said marking means, the latter being removable from said post to permit the insertion thereof through the center hole of the disc record.

6. A structure as specified in claim 5, comprising means for yieldingly supporting the marking means on the upper end of said post, the latter being vertically disposed, and said marking means being rotatable on said post to properly position the engaging portion thereof relatively to the disc record.

7. A structure as specified in claim 5, said post being vertically disposed and having a base at its lower end to form a support for the disc record, whereby said marking means are movable up and down on said post, being removable from the upper end of the post to permit the placing of the disc record on said base.

WILLIAM RAYMOND DUNCAN.
